Primary Examiner — Susan Bennett Hattan*Assistant Examiner* — Lauren D McVey(74) *Attorney, Agent, or Firm* — 24IP Law Group USA, PLLC; Timothy Dewitt(57) **CLAIM**

The ornamental design for a medical trolley cart, as shown and described.

DESCRIPTION

FIG. 1 is a perspective view of the medical trolley cart; FIG. 2 is a front view of the medical trolley cart; FIG. 3 is a back view of the medical trolley cart; FIG. 4 is a right side view of the medical trolley cart; FIG. 5 is a left side view of the medical trolley cart; FIG. 6 is a top view of the medical trolley cart; and, FIG. 7 is a bottom view of the medical trolley cart.

The wire frame lines shown throughout the views are intended to indicate surface contour.

The broken lines depict portions of the medical trolley cart that form no part of the claimed design.

1 Claim, 7 Drawing Sheets(56)
